CLAIM

The ornamental design for packaging for eyewear, as shown and described.

DESCRIPTION

FIG. 1 is a front perspective view;

FIG. 2 is a rear perspective view;

FIG. 3 is a top view of FIG. 1;

FIG. 4 is a front view;

FIG. 5 is a bottom view of FIG. 1;

FIG. 6 is a side view; and,

FIG. 7 is rear view.

The broken lines are included for the purpose of illustrating environmental structure consisting of eyewear, eyewear wipes and an eyewear case and form no part of the claimed designs used in FIGS. 1-7.
